WALL MOUNTED FID

Edward I. Friedman, Warwick, R.I.
(32 Westminster St., Providence, R.I. 02903)

Filed Sept. 21, 1970, Ser. No. 25,078

Term of patent 14 years

Int. Cl. D8—05

U.S. Cl. D8—14

FIG. 1

FIG. 2

FIG. 3

FIG. 4

FIG. 5

FIG. 6

FIG. 1 is a side elevation of a wall mounted fid embodying my new design;

FIG. 2 is a top plan view thereof;

FIG. 3 is a bottom plan view thereof;

FIG. 4 is a rear view thereof;

FIG. 5 is a front view thereof; and

FIG. 6 is a section taken on line 6—6 on FIG. 1.

I claim:

The ornamental design for a wall mounted fid, as shown.
